JOHN GATES, OF PORTLAND, OREGON.

Letters Patent No. 91,010, dated June 8, 1869.

IMPROVEMENT IN STEAM-ENGINE PISTON-PACKING.

The Schedule referred to in these Letters Patent and making part of the same.

To all whom it may concern:

Be it known that I, JOHN GATES, of Portland, in the county of Multnomah, and State of Oregon, have invented a new and useful Improvement in Piston-Packing; and I do hereby declare that the following is a full, clear, and exact description thereof, which will enable others skilled in the art to make and use the same, reference being had to the accompanying drawings, forming part of this specification.

This invention relates to improvements in piston-packing, designed to provide an arrangement whereby a skeleton piston-head, consisting of only one piece of metal, may be used, and the packing-rings may be adjusted without the employment of screws, thereby dispensing with the usual follower, and tightening and adjusting-screws, commonly employed.

Figure 1 represents a transverse section of a piston-head and packing, arranged according to my improvements, taken on the line $x x$ of fig. 2; and

Figure 2 represents a horizontal section of the same.

Figures 3 to 9, represent sectional detail views of certain modifications of my improvements.

Similar letters of reference indicate corresponding parts.

I propose to construct a piston, A, of one piece of metal, as represented in the drawings, having the central hub B, and three segmental webs C, uniting the two side walls.

I also form an inner segmental packing-ring, preferably in three segments, and divided into two parts, or rings a b , the whole being comprised in six pieces.

Each of these segmental parts is provided with a web on its inner face, representing the arc d , supporting at their centres the rollers e , which are provided with the pins f , projecting inward, and taking into holes in the spring g , which is employed to press the packing-ring against the cylinder.

The surfaces of the rollers e are intended to project inward slightly beyond the line of the inner curvature of the segments C, so as to take the pressure of the spring, but not so far as to cause the packing-ring to be forced out beyond the counterbore of the cylinder, which greatly facilitates the entrance of the piston into the cylinder.

Washers may be placed on the pins f , to increase the pressure of the spring g . The said spring is only required to be about two-thirds, or slightly more, of a circle, in order to bear equally upon all the segments. It is, by this arrangement, easily placed in its position around the hub B, and between the side walls of a piston, made of one piece. The rollers e are designed to equalize the pressure on each half of the packing-ring, but, if preferred, they may be dispensed with, and the spring be made to bear directly on the inner faces of the arcs d .

The exterior face of the packing-ring is grooved at each side, for the insertion of the outer segmental rings h .

I also propose to introduce the springs i between the two parts, a and b , of the packing-ring, for pressing them against the side walls of the piston, by which the surfaces may be ground together, to produce a more perfect joint, and also to regulate the admission of steam under the packing-ring. If the working-pressure be one hundred pounds, the springs i may be gauged to a resistance slightly less, say ninety-nine; then when steam enters, it will press the two parts of the ring together, and find its way under the ring, where it will be retained at the latter end of the stroke, when the pressure is reduced by cutting off the springs i , throwing the parts a and b against the walls of the piston, and closing the passage as soon as the pressure falls below the power of the said springs.

Under some circumstances, it may be preferred to make the segments of the packing-ring whole, instead of dividing them into the two parts a and b , under which arrangement it will serve a good purpose; but I prefer to divide it as shown.

In some cases I design to divide the packing-ring into outer and inner rings, x y , as represented in the modifications, figs. 3 to 9, and arrange the spiral or other springs to bear equally upon the said parts, to force them against the walls of the piston, whereby two steam-tight joints are made against each wall, each part, x y , being acted upon separately.

I also propose in some cases to separate the webs d from the inner rings, and arrange them to bear upon the rings in two points z z , as represented in fig. 8, thus applying the action of the springs at six equidistant points.

Having thus described my invention,

I claim as new, and desire to secure by Letters Patent—

1. The combination, with the piston-head A, made in one piece, of the segmental packing-ring, having the interior arcs d , and the spring g , substantially as specified.

2. The combination, with the spring g , and segmental packing-ring, divided into two parts, a and b , of the equalizing-rollers e , substantially as specified.

3. The combination with the segmental packing-ring, divided in two parts, a and b , of the springs i , substantially as specified.

4. The piston-head A, provided with the segmental webs e , and combined with the spring g , and segmental packing-ring, substantially as specified.

JOHN GATES.
